UNITED STATES PATENT OFFICE.

ERNEST D. ANDERSON, OF LONG BEACH, NEW YORK, ASSIGNOR TO E. D. ANDERSON INC.,
OF NEW YORK, N. Y., A CORPORATION OF NEW YORK.

RECEPTACLE OR BAG.

1,334,066.

Specification of Letters Patent. Patented Mar. 16, 1920.

Application filed May 13, 1916. Serial No. 97,215.

To all whom it may concern:

Be it known that I, ERNEST D. ANDERSON, a citizen of the United States, and resident of Long Beach, in the county of Nassau and State of New York, have invented certain new and useful Improvements in Receptacles or Bags, of which the following is a specification.

The object of my invention is to provide a receptacle, such as a bag, made from a single piece of material, such as paper, which may be rendered impervious to moisture either by waxing it on one or both sides, or impregnating it with wax or the like, or both, wherein the two exterior walls on opposite sides of the receptacle will be in a complete unfolded and unitary condition, the walls intermediate said exterior walls being adapted to be folded therebetween, other portions of the receptacle being folded within and between said exterior walls whereby all the edges of the sheet are drawn to the top and adjacent to the mouth of the receptacle and substantially only vertical edge folds show on the exterior thereof. The arrangement is such that the edges of the receptacle at the mouth thereof may be folded in such manner as to securely close the same and the unfolded exterior wall portions of the receptacle afford unbroken surfaces for folding at the mouth portion to effect protection against the entrance of moisture into the receptacle, since a portion of one of such exterior walls may be folded over and inclose all of the other interior folded portions of the sheet at the mouth.

Further objects and features of my invention will be more fully hereinafter set forth and then pointed out in the claim.

Reference is to be had to the accompanying drawings forming part hereof, wherein,

Figura 1 is a face view of a blank or sheet adapted to be folded for the production of my improved receptacle;

Fig. 2 is a perspective view illustrating the blank or sheet partially folded in accordance with my invention;

Fig. 3 is a top view of the blank or sheet folded to form a receptacle, but the mouth portion open to illustrate the relative arrangement of the walls and folds thereof.

Fig. 4 is an end view of the receptacle;

Figs. 5, 6, 7, 8 and 11 are sectional details illustrating different foldings of the

material at the mouth portion of the receptacle for securely closing the same;

Fig. 9 is a side view of Fig. 4, and

Fig. 10 is a perspective illustrating the receptacle with its mouth portion folded.

For the production of my improved receptacle or bag I provide a blank or sheet 1 (Fig. 1) of suitable material, such as paper, which is adapted to be folded upon the crease lines indicated by the dotted lines 65 in Fig. 1 for the production of the receptacle illustrated. If any other shape of receptacle be desired the sheet or blank will be appropriately folded along required crease lines thereof. In the example illustrated the portions 2 of the sheet or blank will, when the latter is folded, constitute main exterior unfolded walls of the receptacle, and the portion 3 will constitute the bottom thereof. Portions 4 of the sheet or 70 blank will constitute the ends or walls of the receptacle intermediate the walls 2. At each of the corner portions of the blank the pairs of triangularly disposed portions 5, 6, are adapted to be folded on the diagonal 75 lines 7, to cause the corresponding pairs of parts 5, 6, to lap or fold against one another within and lapped and concealed by the main exterior unfolded walls 2. The diagonal lines 7 are shown terminating along the 80 edges 1^b, at 7^a, at a point distant from the adjacent edge 1^a. As illustrated, blank 1 is longer than wide, the main wall portions 2 and the triangular portions 6 terminating at the longer edges 1^a of the blank, and the 85 end portions 4 and the triangular portions 5 terminating along the shorter edges 1^b of the blank. When the blank or sheet is to be folded to form the receptacle or bag the parts 4 may be bent upwardly relatively to 90 the bottom part 3 while the pairs of corner portions 5, 6, are bent on the diagonal lines 7 to cause such pairs of portions to fold relatively to one another, as will be apparent from Fig. 2, which illustrates the 95 partially folded blank. By continuing the folding of the blank in an upward direction the pairs of portions 5, 6, at each corner of the blank, may be folded so that one pair will be lapped along the outer wall 2, and the corresponding pair of portions 5, 6, will be lapped within the first named pair, on one side of the bag, and the pairs 5, 6 will be correspondingly lapped on the opposite side of the bag, the wall portions 4 extending 100

105

110

therebetween, in manner illustrated in Fig. 3, whereby an open mouthed bag is formed with the lapped portions 5, 6, along the inner faces of, within and lapped and concealed by, the main exterior unfolded wall portions 2. When the parts have been folded as stated, with the blank or sheet longer than wide, and the diagonal lines 7 terminating at the points 7^a distant from the edges 1^a, the edges 1^b will be below or within the edges 1^a of the portions 2, 6, as illustrated in Fig. 4, wherein the set up receptacle is shown with its mouth portion drawn or pinched closed.

15 In order to securely seal the mouth portion of the receptacle or bag, the lapping portions thereof at 8 (Fig. 4) may be folded or rolled, as illustrated in Figs. 5, 6, 7, 8, 10 and 11, whereby the marginal end portion 20 of one of the walls 2 may fold over and inclose all of the other marginal portions at the mouth of the receptacle. As shown in Fig. 5 the marginal portion of one wall 2 is folded back upon itself, the corresponding extended portions 6 are folded over such folded portion of said wall 2, the portion 2^a of the other wall 2 is folded over the other folded portions, and said parts may be squeezed or compressed forming an effectual closure. In Fig. 6 a substantially corresponding folding arrangement for the mouth parts of the receptacle is illustrated, except that the extreme edge of the portion 2^a is folded between the adjacent portion of wall 2 and its folded end portion. In Fig. 7, a substantially similar folding is afforded at the mouth of the bag with a relatively sharp folding made at 9, with the edge portions, however, not folded back, whereas in Fig. 8 the edge portions of the outer walls 2 are folded back. In Fig. 11 I have illustrated a preferred form of folding the bag mouth, wherein the projecting lapped portions of the bag mouth are given a reverse

bend or are set back at 10, whereas the material may be firmly compressed, and the portions of the bag mouth extending beyond the bend 10 are folded over at an angle to the bag.

In any of the forms of closing the bag mouth set forth, an advantage will be found in that the main exterior unlapped and otherwise unfolded walls 2 will present unbroken surfaces for folding over the mouth of the receptacle or bag, and thereby afford protection against the entrance of moisture into the receptacle or bag because one of the outer unbroken walls folds completely over and incloses all the other mouth portions, and the other of such outer unbroken walls 60 being complete and unbroken within the fold further assists in preventing the entrance of moisture into the receptacle or bag.

Having now described my invention what I claim is:—

A receptacle comprising a single sheet of material folded to form a bottom, exterior walls and interposed walls, with corner portions folded upon themselves and lapping each other along the inner faces of the exterior walls, said bottom, walls and corner portions being united together integrally, the exterior walls being unbroken and unfolded and inclosing said corner portions, the material at the mouth portion being drawn together and folded with a portion of one of the exterior walls inclosing the other mouth portions of the receptacle, the lapped mouth portions being drawn together and having a reverse bend, said portions being folded relatively to the receptacles beyond said bend.

Signed at New York city, in the county of New York and State of New York this 12th day of May, A. D. 1916.

ERNEST D. ANDERSON.
